US0D1043561S

(12) **United States Design Patent** (10) **Patent No.:** **US D1,043,561 S**
(45) **Date of Patent:** **** Sep. 24, 2024**

(54) **CHARGER WITH WIRE**

(71) Applicant: **Shenzhen Chuangdu Technology Co., Ltd.**, Shenzhen (CN)

(72) Inventor: **Caijie Li**, Guangdong (CN)

(**) Term: **15 Years**

(21) Appl. No.: **29/906,159**

(22) Filed: **Nov. 1, 2023**

(51) LOC (14) Cl. **13-02**

(52) U.S. Cl.

USPC **D13/108**

(58) **Field of Classification Search**

(57) **CLAIM**

The ornamental design for a charger with wire, as shown and described.

DESCRIPTION

FIG. 1 is a perspective view of the charger with wire showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
